UNITED STATES PATENT OFFICE

KATHERINE WELSH, OF BROOKLYN, NEW YORK

BEAUTY MASK

Application filed March 20, 1930. Serial No. 437,313.

This invention relates to beauty masks and particularly to devices of this class adapted to be arranged upon the head of a wearer and to brace and support the cheeks, chin and neck as well as to retain the hair in predetermined position; and the object of the invention is to provide a device of the class and for the purpose specified involving a crown portion adapted to be arranged upon the head to form a substantial enclosure for the hair of the head to retain curls, and waves in the hair; a further object being to provide a device which includes in conjunction with the crown, a chin band adapted to encircle the chin of the wearer and having means arranged at the top of the head and at the back of the neck for retaining said band in position; a further object being to provide in conjunction with the crown, a cheek and neck strap adapted to cooperate with said band in supporting the cheeks as well as the chin and neck of the wearer; a still further object being to provide a mask device wherein the several parts are composed of net work material permitting the free flexure thereof and yet presenting a relatively firm but non-binding support for the several parts of the head; and with these and other objects in view, the invention consists in a mask device of the class and for the purpose specified which is of unitary construction, simple and efficient in use, and which is constructed as hereinafter described and claimed.

The invention is fully disclosed in the following specification of which the accompanying drawing forms a part, in which the separate parts of my improvement are designated by suitable reference characters, in each of the views, and in which:

Fig. 1 is a perspective view of the mask device detached with the several parts thereof extended.

Fig. 2 is a side view of the head of a wearer illustrating the mask partially applied thereto.

Fig. 3 is a view similar to Fig. 1 showing the mask completely applied; and,

Fig. 4 is a perspective view of the structure shown in Fig. 3.

In carrying my invention into effect, I pro-

vide a beauty mask consisting of three unitary parts namely a crown 10, chin band 11, and cheek and neck strap 12, all of said parts being preferably composed of net fabric to give ventilation to the parts of the head enveloped thereby as well as to provide a non-binding support for the parts of the head in connection with which the mask operates.

The crown 10 is fashioned to fit over the top, sides and back of the head to form an enclosure for the hair to retain the same against displacement, especially when curled or waved, and the peripheral edges of the crown are provided with a finish tape or strip 10a of lace or any other suitable material, and at the opposite sides of the crown are two guide and retaining straps 13 in conjunction with which the band 11 operates.

The band 11 is of the general form seen in Fig. 1 of the drawing, the major portion of said band being comparatively wide and terminating in tapered ends 11a and 11b having straps 14, the end 11a being fixedly attached to the crown 10. The central portion of the band 11 is provided with a dart 11c at one side edge thereof in order that said band will conform with and fit snugly about the chin, and the peripheral edges of the band are reinforced by a lace or other tape 15. Two other straps 16 are attached to the rear side edge of the band 11 and are adapted to be passed around the back of the neck and tied as indicated at 16a, note Figs. 2 and 3. The straps 14 are tied at the top of the head as seen at 14a. The strap 12 is attached to the front edge of the crown 10 and projects beyond said crown to fit around the head adjacent the forehead. The free end portions 17 of said strap after passing downwardly over the cheeks of the wearer are crossed beneath the chin and extended around the neck and are tied together as seen at 17a. In the accompanying drawing, the strap 12 is shown arranged upon the band 11, but this arrangement may be reversed if desired; that is to say, the band 11 may be arranged outwardly of the strap 12 when the device is mounted upon the head of the wearer. The strap 10 has reinforced edgings 18 corresponding to the edgings of the other parts, it being ap-

100

parent that all of the parts 10, 11 and 12 are composed of the network material. It will also be noted on considering Fig. 4 of the drawing that the central portion of the crown 5 as well as the strap 12 is the same as indicated at 19 to properly shape the crown upon the head of the wearer.

In the use of the device, the crown 10 is first placed upon the head and the end portion 11b of the band 11 is passed around the chin and upwardly at the opposite side of the head through the strap loop 13 and the strips 14 tied at the top of the head to firmly support said band, after which the straps 16 are tied at the back of the neck. In the latter operation, the band 11 is drawn backwardly to draw the flesh of the cheeks, chin and part of the neck backwardly to correct sagging facial muscles as well as loose, flabby jowls, also serving to support the mouth and to correct what is known as drooping mouth lines, which results are also brought about by the strip 12, the ends of which are crossed beneath the chin after drawing downwardly upon said strap ends to retain the cheeks in proper position, the ends 17 being brought around the neck and tied at the back of the neck, the latter ends serving to support the neck and lower chin muscles, to brace and support the various parts of the face referred to, including the neck, to maintain a youthful contour.

It will be understood that my improved mask is designed for use primarily by women and is preferably applied to the head prior to retiring or at any other time and its constant use will serve to maintain the desired youthful facial contour and avoid undue wrinkling of the face, it being understood that the mask supports practically all of the facial muscles requiring the brace and support afforded by my improved device.

By employing in the construction of the several parts, a network fabric, preferably of a soft texture, it will be understood that while the muscles are firmly supported in desired position, there are nevertheless yielding characteristics to this firm support which renders the device comfortable in use, and it will also be understood that my improved device may be used as a bandage in bracing and supporting various parts of the head.

While I have shown certain details of construction for carrying my invention into effect, it will be understood that I am not necessarily limited to these details, and various changes therein and modifications thereof may be made within the scope of the appended claims without departing from the spirit of my invention or sacrificing its advantages.

Having fully described my invention, what I claim as new and desire to secure by Letters Patent, is:

65 1. A mask of the class described compris-

ing a crown portion of openwork fabric adapted to be arranged upon and cover the hair of the head, a strap at the front of said crown portion, the ends of said strap projecting beyond the crown and adapted to be arranged over the cheeks of a wearer, crossed beneath the chin of the wearer and passed around the neck and attached at the back of the neck to support the facial muscles of the wearer.

2. A mask of the class described comprising a crown portion of openwork fabric adapted to be arranged upon and cover the hair of the head, a strap at the front of said crown portion, the ends of said strap projecting beyond the crown and adapted to be arranged over the cheeks of a wearer, crossed beneath the chin of the wearer and passed around the neck and attached at the back of the neck to support the facial muscles of the wearer, and a chin band, one end of which is attached to one side portion of the crown, said band being adapted to be passed around the chin of the wearer, and the other end thereof detachably coupled with the first named end.

3. A mask of the class described comprising a crown portion of openwork fabric adapted to be arranged upon and cover the hair of the head, a strap at the front of said crown portion, the ends of said strap projecting beyond the crown and adapted to be arranged over the cheeks of a wearer, crossed beneath the chin of the wearer and passed around the neck and attached at the back of the neck to support the facial muscles of the wearer, a chin band one end of which is attached to one side portion of the crown, said band being adapted to be passed around the chin of the wearer and the other end thereof detachably coupled with the first named end, and means attached to the side portions of the band for drawing the same backwardly, said means being detachably coupled at the back of the neck.

4. A mask of the class described comprising a crown portion of openwork fabric adapted to be arranged upon and cover the hair of the head, a strap at the front of said crown portion, the ends of said strap projecting beyond the crown and adapted to be arranged over the cheeks of a wearer, crossed beneath the chin of the wearer and passed around the neck and attached at the back of the neck to support the facial muscles of the wearer, and said strap being composed of openwork fabric.

In testimony that I claim the foregoing as my invention I have signed my name this 17th day of March, 1930.

KATHERINE WELSH.
